UNITED STATES PATENT OFFICE.

CHARLES S. FARRER, OF DUNMORE, PENNSYLVANIA.

TIPPLE.

SPECIFICATION forming part of Letters Patent No. 617,087, dated January 3, 1899.

Application filed April 25, 1898. Serial No. 678,755. (No model.)

To all whom it may concern:

Be it known that I, CHARLES S. FARRER, of Dunmore, in the county of Lackawanna and State of Pennsylvania, have invented certain new and useful Improvements in Tipples, of which the following is a full, clear, and exact description.

This invention relates to dumping apparatus or tipples, but more particularly to such devices as are employed for conveying and dumping material from mines into railway-cars and the like for transportation purposes.

The primary object of the invention is to provide a tipple which will be under the complete control of the operator and which will readily hold the car on the tilting platform or rail-section, so that the material may be deposited from the car and the car automatically returned to its normal position.

A further object of the invention is to provide simple and efficient mechanism for holding the car on the tilting platform, so as to be properly emptied of its contents, and to provide automatically-actuated means by which the tilting platform may be held in its normal position or which will permit the platform to be tilted or rocked to an inclined position.

With these and other objects in view the invention consists in the construction and combination of the several parts, substantially as hereinafter described, and then pointed out in the claims at the end of the description.

Referring to the accompanying drawings, forming a part of this specification, Figure 1 is a longitudinal section taken on the line I I of Fig. 2, showing in full lines a side elevation of the car and tilting platform, their normal position, and in dotted lines the car and platform in a tilted or inclined position. Fig. 2 is a plan view of the tipple, a portion of the operating mechanism being broken away and brought together to more clearly illustrate the working of the same. Fig. 3 is a fragmentary rear end view of the tilting platform and mechanism with the car in the position shown in Fig. 1. Fig. 4 is a vertical sectional view taken on the line IV IV of Fig. 3, illustrating one position of the operating mechanism. Fig. 5 is a similar view to Fig. 4, except that the mechanism is shown in another position; and Fig. 6 is a sectional view

of the latch or locking device for the tilting platform.

The tilting platform or rail-section 10 has the side or rail beams 11 connected together by suitable stay-rods, so as to be rigidly held apart, and has a plate 12 secured between said beams. Projecting outwardly from the beams 11 are racks 13, having teeth on their under surface, engaging the teeth of the curved or scroll racks 14, these latter racks being suitably supported by the usual or any preferred form of stationary framework. The rail or side beams 11 form a continuation of the usual track and are adapted to support the cars 15, as shown in Figs. 1 and 3.

For the purpose of properly holding the car upon the tilting platform or rail-section 10 prior to and while in a tilted position I arrange suitable stops, as 16, so as to move with the platform. As shown, these stops are secured to a shaft 17, journaled in the platform 10 and arranged adjacent to the beams 11. These stops have hooks or curved projecting portions 18, adapted to engage the flanges of the wheels 18^a of the car, and counterbalances or weights 19, projecting outwardly from the shaft in an opposite direction to the hooks 18. The stops have a lower straight or plane surface 20, which when in the position shown in Figs. 1, 3, and 4 is adapted to be engaged by the cams or knees 21, the latter being secured to the transverse shaft 22, journaled in pendent portions or bearings 22^a of the platform 10. The knees 21 are adapted to be rocked or oscillated with the shaft 22, and when in the position shown in Figs. 1 and 4 the straight or plane surfaces 23 will rest against the lower surfaces 20 of the stops 16, so as to rigidly hold the same in an upright position, a plate 23^a being secured to each pendent portion 22^a, which limits the downward movement of the knees when the latter are operated to permit the stops 16 to lower. This transverse shaft 22 has a pulley or sprocket-wheel 24, around which may be arranged a chain 25, which passes over a similar pulley or sprocket-wheel 26, secured to a suitably-supported shaft 27, said latter shaft being held in suitable stationary bearings or in bearings which will yield slightly to the movement of the

tilting platform. The shaft 27 has a pulley or sprocket-wheel 28 thereon, around which passes a chain 29, secured at one end to said pulley or sprocket-wheel and at its other end to an oscillatory lever 30, so that when the lever is operated the shaft 22 will be rocked in its bearings by means of the chain 25, which passes around the pulleys or sprocket-wheels 24 and 26. The operating-lever 30 is arranged on a bolt or shaft 31, which is secured in a suitable bracket 32, and on the bolt 31 is another lever 33, similar to the lever 30, which is connected by a chain 34 to a pulley 35, this latter pulley being secured to the shaft 27 and having the chain thereon arranged to rotate the same and the shaft in an opposite direction to that secured by the chain 29 and pulley 28.

The shaft 22 intermediate the stops 16 is provided with an arm or crank 36, to which is pivoted a rod 37, this rod being passed through and suitably supported in a bracket 38, arranged upon the platform 10, the plate 12 of the platform being cut away, so as to permit the arm 36, as well as the stops 16, to move above the same. On the rod 37 and on opposite sides of the bracket 38, which is secured to the plate 12 of the platform, are the springs 39 and 40, which are opposed to each other and held adjustably upon the rod 37 by means of the lock-nuts 41, the function of the spring 39 being to start the stops 16, so that they will be thrown suddenly downward, while the spring 40 is adapted to assist in arresting the downward movement of the stops and the connecting mechanism.

To release the tilting platform or to hold the platform in a horizontal position, a rod, as 42, is connected at one end to the stops 16 and at its other end to a slide or plunger 43, which is held in brackets 43^a, secured to the beams 11 of the tilting platform. The plungers or slides 43 when the stops are in a raised position are adapted to engage the ends of locking devices or latches 45, which are slidably held in suitable casings 46, secured to a support 47, on which support may be also arranged a portion of the track, as 47^a. Each latch 45 is normally pressed outward by a spring 48, Fig. 6, arranged in the casing, and is prevented from being thrown too far by a bolt 49, which passes through the casing and a slot 50 in said slide, so that when the stops are in the position shown in Fig. 5 the spring 48 will force the latch or locking device outward beneath the end of the adjacent beam 11, so as to hold the platform in a horizontal position; but when the stops are raised, as in Fig. 4, each plunger 40 through the reach or connecting-rod 42 will engage the end of the latch or locking device 45 adjacent thereto and force the same away from the end of the platform, so that the latter may lower by the weight of the car.

65 The operation of the invention will be readily understood from the foregoing de-

scription when taken in connection with the accompanying drawings.

The cars are run onto the heel of the tilting platform or rail-section 10 in the direction indicated by the arrow in Fig. 1. When the first two wheels of the car run on the end of the platform, the operator pulls back the lever 30, which operates the pulley or sprocket-wheel 28, and through the shaft 27, pulleys 26 and 24, shaft 22, and cams or knees 21 will throw the stops 16 to the position shown in Figs. 1 and 4 to receive the flanges of the forward wheels of the car. Just prior to the engagement of the forward wheels of the car with the stops 16 the plungers or slides 43 through the rods 42 will disengage the latches or locking devices 45 from the ends of the platform 10. The weight of the car will now tilt or rock the platform 10 on the scroll or curved racks 14 to an inclined position, so that the material may be properly deposited into a receptacle provided therefor, as shown in dotted lines in Fig. 1. During the movement of the cars and tilting platform the fulcrum or weight is shifted, so that as the material passes out of the car the weight of the car and the rear end of the platform will be sufficient to automatically restore the platform with the car thereon to its normal or horizontal position. After the car has been emptied of its contents the lever 33 is operated, and through the chain 34, pulley or sprocket-wheel 35, shaft 27, pulleys 26 and 24, and shaft 22 the knees or cams 21 will be thrown downward, so as to rest against the stop-plates 23^a, as shown in Fig. 5. As soon as the knees are released the spring 39 through the rod 37, arm 36, and shaft 22 will start the stops 16, so that by the weight thereof and the connecting mechanism the hooks 18 of the stops will be thrown suddenly downward to the position shown in said figure. This movement of the stops through the rods 42 will withdraw the slides or plungers 43, so that the latches or locking devices 45 will engage the lower surface of the platform, so as to rigidly hold the same in a horizontal position. The car may now be run off the tilting platform ready for the next full car. Ordinarily in operating the levers after the stops have been thrown to an elevated position the lever 30 is again thrown forward, and in like manner the lever 33 after being operated for throwing the knees or cams 21 downward is also thrown forward and left in this position, allowing the slack in the chains to be taken up by the movement of the platform.

I thus provide simple and efficient means whereby the movement of the car and tilting platform or rail-section is under complete control of the operator, so that the car may be readily emptied and automatically returned to a horizontal or raised position.

While I have described a particular form of tilting platform, it is to be understood that

this may be of any desired construction and arranged in any suitable manner and that the means for operating the stops, as well as some of the other parts, may be varied without departing from the spirit of my invention.

Having thus described my invention, I claim as new and desire to secure by Letters Patent—

1. In a device of the character described, 10 the combination with a suitably-supported tilting platform or rail-section, of mechanism adapted to hold the car on said platform, together with means for holding one end of said tilting platform in a horizontal position, said 15 means being automatically actuated in one direction and positively actuated in the opposite direction by the car-holding mechanism when the latter is being moved in position to hold the car, substantially as described.
2. In a tipple, the combination with a suitably-supported tilting platform adapted to support a car, mechanism carried by the platform for holding the car thereon when in a tilted position, independent locking devices 25 engaging the platform when in its normal position, and means actuated by the car-holding mechanism for releasing the locking devices, substantially as described.
3. In a tipple, the combination with a suitably-supported tilting platform or rail-section adapted to support a car, means for holding the car when the platform is in a tilted position, spring-pressed latches engaging the tilting platform when in its normal position, 35 plungers carried by the platform adapted to release the latches, together with means for operating the plungers, substantially as described.
4. The combination with a tilting platform 40 or rail-section adapted to support a car, of stops adapted to hold the car on the platform when in the tilted position, means for operating the stops, independent locking device or devices engaging the platform when in its 45 normal position, and means operated by the movement of the stops for releasing the locking device or devices to permit the platform and car to tilt, substantially as described.
5. In a device of the character described, 50 the combination with a suitably-supported tilting platform, of means for holding the platform in its normal position, stops carried by the platform and forming a rest for the cars, knee or knees adapted to engage and move 55 the stops, and means for operating the knee or knees, substantially as described.
6. In a device of the character described, the combination of the vertically-movable stops, a shaft to which the stops are secured, 60 knees or cams for positively operating the stops in one direction, and a spring to assist in throwing the stops in the opposite direction, substantially as described.
7. In a tipple, the combination of suitable 65 stops adapted to engage the forward wheels

of the car, means for positively operating the stops in one direction, together with springs, one of which assists in suddenly throwing the stops in the opposite direction, while the other spring assists in arresting the downward movement of the stops and connected parts, substantially as described.

8. In combination, a shaft, stops secured to the shaft, knees or cams for engaging the stops and positively operating the same in one direction, means assisting to throw the stops to their normal position, a shaft to which the knees are secured, and means for rotating the shaft in opposite directions, substantially as described.

9. In a tipple, the combination with stops adapted to engage the wheels of the car, knees or cams for positively operating the stops in one direction, a shaft to which the knees are secured, levers, together with pulleys and a flexible connection between the levers and the shaft for operating the latter in opposite directions, substantially as described.

10. In a tipple, a shaft, stops adapted to engage the wheels of a car secured to said shaft, 90 an arm secured to the shaft, a rod secured to the arm, a bracket through which the rod passes, opposed springs arranged on the rod on opposite sides of the bracket, together with means for throwing the stops in position for 95 engaging the wheels of the car, substantially as described.

11. In a device of the character described, the combination with a tilting platform or rail-section, a shaft journaled in the platform transversely thereof, stops secured to the shaft and adapted to engage the wheels of the car when supported by the platform, a rod connected to the shaft, a spring arranged on the rod to assist in throwing the stops 105 downward, a second spring also arranged on the rod to assist in arresting the movement of the stops, knees adapted to engage the stops, stop-plates for the knees, a shaft to which the knees are secured, together with levers and connections for operating the shaft in opposite directions so as to throw the stops in one direction or to permit the said stops to move in the opposite direction, substantially as described.

12. In a device of the character described, the combination with movable stops having hooks or curved portions, counterbalances for said hooks or curved portions, and a plane lower portion, of knees also having a plane 120 portion adapted to engage the straight portion of the hooks, and means for operating the knees so as to rigidly hold the hooks in an elevated position, substantially as described.

CHARLES S. FARRER.
